P. RONK

ENDLESS ROPE BELT AND METHOD OF MAKING THE SAME

Filed Oct. 15, 1923

Patented Nov. 11, 1924.

UNITED STATES PATENT OFFICE.

PAUL RONK, OF LADOGA, INDIANA.

ENDLESS ROPE BELT AND METHOD OF MAKING THE SAME.

Application filed October 15, 1923. Serial No. 668,625.

To all whom it may concern:

Be it known that I, PAUL RONK, a citizen of the United States, and a resident of Ladoga, county of Montgomery and State of Indiana, have invented a certain new and useful Endless Rope Belt and Method of Making the Same; and I do hereby declare that the following is a full, clear, and exact description thereof, reference being had to the accompanying drawings, in which like numerals refer to like parts.

This invention relates to the method of constructing an endless rope belt, or a belt formed of cables or other similar material adapted for use as a fan belt for motors, or any machine equipped with V pulleys.

The main feature of the invention resides in the method of so constructing a belt of this character that the point of joinder of the free ends will be not only concealed but will be so arranged that there will be no enlargement of the belt at that point. To accomplish this the free ends of the belt are so interwoven therein as to be distributed throughout the entire portion thereof, whereby there will be no point of weakness in its tensile strength.

The full nature of this invention will be understood from the accompanying drawings and the following description and claims.

In the drawings Fig. 1 is a plan view showing the completed belt. Fig. 2 is a section taken on the line 2-2 of Fig. 1. Fig. 3 is a view showing a section of the belt with a portion thereof broken away for showing the interior structure thereof. Fig. 4 is the same as Fig. 1 showing the first winding of the belt.

In the drawings there is shown an endless rope belt constructed of the usual type of twisted rope 10 having a plurality of strands 11. As shown herein the rope is formed of three strands. In forming the belt, the rope is looped according to the size of belt desired, the periphery of the loop being substantially the same as the periphery of the finished belt. In order to hold the looped rope in position to give the proper size thereto, the rope is tied together by a binding twine at 12. This tying is merely to hold it temporarily in place and need have no appreciable binding strength. In looping the rope and tying it in position, it is so arranged that there is a free end of a

length substantially that of one half the periphery of the finished belt. This shorter free end is unraveled to provide the several strands 13, being three in number as shown herein. These strands are layed about the periphery of the body or central core portion 14, terminating at a point substantially opposite to the point of tying. The other end 15, which is of appreciable length is then wound about the body portion of the core 14, as shown in Fig. 4, binding in the strands 13. As the strands 13 have been separated and lie about the periphery of the core 14, they take up no appreciable space so that the diameter of the finished belt will not be affected. Upon the core being wound spirally by the rope 15 through one lap thereof, the winding is continued until, as shown herein, seven laps have been made, bringing the loose end of the winding 15 to the point of beginning at 12. The rope is then cut and the other end of the winding rope 15 is unraveled to provide the three strands 16 which are thereupon threaded intermediate the winding 15 and the core 14 a sufficient distance to meet end of the strand 13, opposite 12. This may be done by twisting the winding, and thereby loosening it on the core while the raveled ends are threaded therebetween and then, upon stretching the finished belt and pulling the winding into position, the free end will be firmly held in place. Obviously the tighter the belt is pulled the more firmly will the free ends thereof be gripped.

It will be observed from the above that in constructing a belt of this character the finished product will show no connected ends and there will be no enlargement at points or joinder, nor any appreciable enlargement in diameter throughout the entire belt by reason of the interwoven strands. Thus, an endless rope belt of maximum tensile strength is produced having the same diameter throughout with no single or apparent point of joinder.

The invention claimed is:

1. A method of forming an endless rope belt consisting of looping the rope to form a core, unraveling one free end thereof and arranging it to lie adjacent said core, winding the other free end about said core to provide an outer winding, unravelling the free ends of said winding after the completion thereof for providing a plurality of strands,

and threading said strands between said core and outer winding for concealing and securing the end thereof.

2. The method of forming an endless rope belt consisting of looping the rope and binding it in looped position to form a core, unraveling one free end thereof and arranging it to lie adjacent said core, winding the other free end about said core and unraveled end so as to enclose the same and provide an outer winding therefor, and threading the free end thereof between said core and winding for concealing and securing the same.
- 15 3. The method of forming an endless rope belt, consisting of looping the rope and binding it in looped position to form a core, unraveling one free end thereof into a plurality of strands and arranging said strands so as

to lie adjacent substantially one half of said core, spirally winding the free end of the rope about said core and strands making a plurality of complete revolutions so as to entirely enclose said core and strands and provide an outer enclosing winding, unraveling the free end of said winding to form a plurality of strands, twisting said winding so as to loosen the same about said core, and threading said last mentioned strands between said winding core so as to be enclosed and clamped therebetween, and stretching said belt so as to pull said windings taut about said core thereby firmly securing the free ends therein.

In witness whereof, I have hereunto affixed my signature.

PAUL RONK.
